UNITED STATES PATENT OFFICE.

HIRAM GORDON, OF PORTSMOUTH, OHIO, ASSIGNOR TO S-ELBY SHOE COMPANY, OF PORTSMOUTH, OHIO, A CORPORATION OF OHIO.

PRESSER PAD.

Application filed April 6, 1922. Serial No. 550,122.

To all whom it may concern:

Be it known that I, HIRAM GORDON, citizen of the United States, residing at Portsmouth, in the county of Scioto and State of Ohio, 5 have invented certain new and useful Improvements in Presser Pads, of which the following is a specification.

This invention relates to improvements in presser pads used in shoemaking, and has 10 for its particular object to provide a device of this character which will perfectly press a layer of thin grain leather against the entire surface of the out-sole of the shank of the shoe and also up into the breast of a full 15 wooden heel known as the Louis type.

A further object is to provide a presser pad of the character above described which will adjust itself to fit Louis heels of different sizes and shapes, and save approximately 20 fifty per cent in time over the method now practised in securing the layer of grain leather in place.

The grain leather layer which partly finishes the underside of the shoe, usually covers 25 the shank and the front face or breast of the heel and is glued thereto, and the methods now practised in pressing this thin layer of leather in place, usually by strings and steaming processes, is an arduous, slow and 30 tedious task to make the layer adhere evenly and perfectly throughout its entire area as it should be in first class goods.

These and other objects hereinafter set forth are attained by the means illustrated 35 in the accompanying drawing, in which:—

Figure 1 is a perspective view of the improved device secured in pressing position to a shoe.

Figure 2 is a side elevation of a shoe showing 40 the improved device in section and applied in pressing position.

Figure 3 is a cross-sectional view of the presser pad, and

Figure 4 is a perspective view of the 45 presser pad.

Similar reference numerals in all of the figures of the drawing designate like parts.

Referring to the drawing 6 designates the presser pad and 7 the holder therefor. The 50 presser pad is preferably made of pure soft rubber and formed with a concave groove 8 which extends around at least three sides thereof, and forming side flanges 9. The groove 8 is curved to conform to the under-

5 side of the shank and front face of the heel of the shoe, both longitudinally and transversely, and on its rear face, adjacent its flat side, is preferably formed with a convex curved protuberance 10 which is adapted to fit into the usual curved hollow formed in 60 the heel. The pad is provided with a rigid boxing or holder 7 preferably formed of steel, and said boxing is formed with a roughened top surface 11, and is secured to the presser pad by the screw-bolts 12 which 65 preferably extend entirely through the presser pad from one side leg 13 to the opposite leg 13' in which they are threaded.

After the grain leather layer has been 70 placed in position, on the sole shank, and against the face of the heel, (it being understood that suitable glue has first been applied) the presser pad is then placed in position between the shank and the heel, and is forced and retained in position by a screw-clamp which consists of a yoke formed with 75 a connecting bar 14 and side-arms 15, the connecting bar being preferably tapered on its inner side to engage between the raised portion of the roughened surface 11, a cross-head 16 rigidly connected between the free ends of the side-arms 15, and an adjusting screw 17 which has a threaded engagement 80 with said cross-head 16 and is provided with a turn-handle 17' at one end and a pivoted 85 foot 18 at its opposite end adapted to engage the portion of the shoe-last exposed at the open side of the shoe.

The pivoted foot 18 is preferably connected to the adjacent end of the screw 17 by a 90 ball and socket joint 19 and on its free side is provided with a pin-projection 20 which is adapted to engage a hole in the top of the exposed portion of the shoe-last.

As the screw-clamp is tightened, the 95 presser pad is forced tightly and closely in position against the grain layer, and as the presser pad is being forced, the grooved contour thereof gradually smooths out the layer and fits it snug over the surfaces to be covered. The presser pad is retained in the clamped position until the adhesive has set 100 sufficiently to hold the layer in place.

Groove 8 is formed sufficiently deep to accommodate shanks and heels of various 105 sizes, and roughened face of the steel-boxing or holder, together with the ball and socket joint of the screw, enables the clamping

means to be adjusted to different positions with respect to the presser pad to secure the best results.

Having thus fully described the invention, 5 what is claimed is:

1. A device for the purpose described, comprising a presser pad formed of a block of soft elastic material and provided with a concave groove around its periphery, said 10 block being of such dimensions as to simultaneously fit and cover the exposed face of the shank of a shoe and the breast of the heel thereof, and means for clamping the device on a shoe.
- 15 2. A device for the purpose described, comprising a presser pad formed of a block of soft elastic material and provided with a concave groove around its periphery, said block being of such dimensions as to simultaneously fit and cover the exposed face of the shank of a shoe and the breast of the heel thereof, said pad also being formed with a projecting protuberance at one side thereof to fit a hollow in the breast of the 20 heel, and means for clamping the device to a shoe.
- 25 3. A device for the purpose described, comprising a presser pad formed of a block of soft elastic material and provided with a concave groove around its periphery, said block being of such dimensions as to simultaneously fit and cover the exposed face of the shank of a shoe and the breast of the heel thereof, and a clamping means engaging said rigid holder for forcing the pad in position and causing it to assume the shape of the engaged parts 30 of the shank and heel.

35 simultaneously fit and cover the exposed face of the shank of a shoe and the breast of the heel thereof, and a rigid holder fixedly secured to one side of the pad.

4. A device for the purpose described, comprising a presser pad formed of a block of soft elastic material and a rigid holder fixed to one side thereof, said block being of such dimensions as to simultaneously fit and 40 cover the exposed face of the shank of a shoe and the breast of the heel thereof, and a clamping means engaging said rigid holder for forcing the pad in position and causing it to assume the shape of the engaged parts 45 of the shank and heel.

5. A device for the purpose described, comprising a presser pad formed of a block of soft elastic material and a rigid holder fixed to one side thereof, said block being of such dimensions as to simultaneously fit and cover the exposed face of the shank of a shoe and the breast of the heel thereof, and a clamping means engaging said rigid holder for forcing the pad in position and causing 50 it to assume the shape of the engaged parts of the shank and heel, said clamping means embodying a yoke adjustably engaged with the rigid holder and the exposed portion of a shoe-last placed within the shoe.

55 In testimony whereof I affix my signature.
HIRAM GORDON.
